UNITED STATES PATENT OFFICE.

FREDERICK C. RAYMOND, OF NEW YORK, N. Y.

DESIGN FOR A HOOK FOR GARMENT-FASTENERS.

SPECIFICATION forming part of Design No. 25,699, dated June 30, 1896.

Application filed March 7, 1896. Serial No. 582,267. Term of patent 14 years.

To all whom it may concern:

Be it known that I, FREDERICK C. RAYMOND, a citizen of the United States, residing at the city of New York, in the county 5 and State of New York, have invented and produced a new and original Design for the Hooks of Garment-Fasteners, of which the following is a specification, reference being had to the accompanying drawings.

10 In the drawings, Figures 1 and 2 represent in perspective two views of a hook for a garment-fastener embodying my design, Fig. 1 being a front view and Fig. 2 a back view.

A hook embodying my design consists of a 15 stock or back portion A and a reverted tongue B. The stock or back portion A tapers from the root *a* of the tongue B in converging straight lines 3 3, which are united in the tail of the stock by still further converging lines 20 4 4 and a cross-line 5, forming four angles

6 6 7 7. The tongue has its sides slightly converging, as shown at 8 8, and its tip 9 rounded, and from the sides of the stock A, near the root *a* of the tongue, there project outwardly two lugs *b*, which terminate in 25 multangular form, as shown at 9 9. The hook has a central opening *c d*, which runs through the stock and tongue and the sides of which are straight and approximately parallel with the exterior lines 3 3. The end *c* of this opening is straight and parallel with the end 5 of the stock.

What I claim is—

The design for the hook of a garment-fastener, substantially as herein shown and described.

FREDERICK C. RAYMOND.
